(57) **CLAIM**

The ornamental design for a portable bag hanging apparatus, as shown and described.

DESCRIPTION

FIG. 1 shows a front perspective view of a portable bag hanging apparatus showing my new design;
FIG. 2 shows a front elevation view thereof;
FIG. 3 shows a rear elevation view thereof;
FIG. 4 shows a left elevation view thereof;
FIG. 5 shows a right elevation view thereof;
FIG. 6 shows a top plan view thereof;
FIG. 7 shows a bottom plan view thereof;
FIG. 8 shows a perspective view thereof, the broken line features are shown in a different state of use;
FIG. 9 shows a portable bag hanging apparatus in an alternate state of use. The additional broken lines show the environment of use;
FIG. 10 shows a portable bag hanging apparatus in an alternate state of use. The additional broken lines show the environment of use;
FIG. 11 shows a portable bag hanging apparatus in an alternate state of use. The additional broken lines show the environment of use;
FIG. 12 shows a portable bag hanging apparatus in an alternate state of use. The additional broken lines show the environment of use; and,
FIG. 13 shows a portable bag hanging apparatus in an alternate state of use.

The broken lines shown in the drawings depict portions of the portable bag hanging apparatus that form no part of the claimed design. The additional broken lines in FIGS. 9-12 depict the environment of the article and forms no part of the claimed design. The difference in the density of stipple shading between surfaces depicts a contrast of appearance.
